AUTOMOBILE WINDOW AWNING

Filed Dec. 22, 1926

FIG. I

FIG. II

FIG. III

FIG. IV

FIG. V

INVENTOR
C. E. HENDRIX
BY J. G. Cook
ATTORNEY

UNITED STATES PATENT OFFICE.

CHARLES E. HENDRIX, OF JEFFERSON CITY, MISSOURI.

AUTOMOBILE WINDOW AWNING.

Application filed December 22, 1926. Serial No. 156,283.

My invention relates to an automobile window awning, and has for its object to provide a simple and highly efficient structure of this character the width of which 5 can be readily adjusted and the parts locked in adjusted position. Another object is to provide a simple and highly efficient locking mechanism for holding the awning securely in position in the window frame without the 10 employment of screws or bolts, which tend to mutilate the opening in which the awning is secured.

With the foregoing and other objects in view, the invention comprises the novel construction, combination and arrangement of parts hereinafter more specifically described and illustrated in the accompanying drawings, wherein is shown the preferred embodiment of the invention. However, it is 20 to be understood that the invention comprehends changes, variations and modifications which come within the scope of the claims hereunto appended.

Fig. I is a perspective view of my improved awning attached in the front door window of an automobile.

Fig. II is a cross sectional view of my improved awning showing the method of attachment of the same in a window frame.

Fig. III is a top plan view of my improved awning.

Fig. IV is a front elevation of my improved awning with the awning cover removed.

Fig. V is an enlarged detail showing the means of fastening my improved awning in the automobile window frame.

In the drawing 1 and 2 designate wire members provided with arms 3 and 4 bent 40 at right angles to the portions 1 and 2. 5 is a cylindrical member adapted to fit over the arms 3 and 4, respectively, and to bridge any gap between the ends of these arms. 6 is a hollow member adapted to fit over the arms 45 7 and 8 at the inner section of the awning frame and parallel to the arms 3 and 4. This hollow member 6 is provided with a series of perforations 9 and 10 to receive screws 11 and 12, respectively. The purpose of this member 6 is to lock the frame in such adjusted position as to width as may be desired, after such adjustment has been determined.

13 is the awning cover, preferably of awning cloth. 14 and 15 designate relatively 55 U-shaped members attached to downwardly

extending arms 16. (See Figs. II and IV.) These U-shaped members pass through perforations provided in the downwardly extending arms 16 and are adapted to be moved inwardly and outwardly by virtue of the screws 17 and 18, also mounted in said arms 16. Heads 19 are provided on the free ends of the members 14 and 15 to prevent them from passing through the perforations in the arm 16. 20 are serrations provided on the members 14 and 15 to cause them to firmly grip against the window casing when the awning is placed in position. 21 are serrations provided on the arms 3 and 4 and 7 70 and 8 to prevent the awning cloth from slipping when stretched upon the awning frame. In Fig. V the window frame opening is designated by A.

In the operation of my device, the size of 75 the window opening is first determined and the parts shown in Figs. III and IV adjusted to the proper width, and the screws 11 and 12 are placed in the proper perforations in the hollow member 6 and screwed into the 80 arms 7 and 8, respectively, thus securely holding the parts in the proper adjusted position. The frame is then covered with the awning cloth, which is prevented from slipping by the serrations 21, at which time 85 the device is ready to be inserted in the automobile window opening.

The screws 17 and 18 are unscrewed so that the U-shaped members 14 and 15, as shown particularly in Fig. IV, are retracted 90 sufficiently so that the arms 16 may be adjusted to the window frame openings, and the arms 14 and 15 duly inserted in the slots therein. The screws 17 and 18 are then operated to press outwardly the U-shaped members 14 and 15, so that they will firmly contact with the window frame opening into which they have been inserted and prevented from slipping by the serrations 20 on said members 14 and 15. It will thus be obvious 95 that a very tight connection is had between the window frame opening and the arms 16, so as to effectively hold said awning securely in operative position. The awnings may be quickly and conveniently removed when desired. The awning cloth may be easily replaced or removed for the purpose of cleaning or washing.

I claim:

1. In an automobile window awning, an 110 awning frame adapted to carry an awning cover, an arm secured to said awning frame

having an opening therein to receive a movable securing member, and means for moving said securing member into position to lock said awning frame in an automobile window 5 casing, said means comprising a threaded member mounted in said arm, one end of said threaded member being adapted to contact with said movable securing member, substantially as described.

10. 2. In an automobile window awning, an adjustable awning frame adapted to carry an awning cover, means for securely holding said awning frame in adjusted position, an arm secured to said awning frame and provided with 15 an opening therein to receive a movable securing member, and a threaded bolt associated with said arm and contacting with said securing member whereby said securing member is moved into position to lock said awning frame 20 in an automobile window casing, substantially as described.

3. In an automobile window awning, an adjustable awning frame adapted to carry an awning cover, said awning frame being provided with inner and outer arms, a hollow member adapted to fit over the outer arms of said awning frame and bridge the gap between said arms when said awning frame is adjusted, another hollow member fitted over 25 the inner arms of said awning frame, said second-named hollow member being provided with perforations to receive screws adapted to enter said last-named arms of said awning frame when said awning frame is in adjusted 30

position, an arm secured to said awning frame 35 and provided with an opening therein to receive a movable securing member, and a threaded bolt associated with said arm and contacting with said movable member whereby said movable member is caused to lock said 40 awning frame in an automobile window casing, substantially as described.

4. In an automobile window awning, an adjustable awning frame adapted to carry an awning cover, said awning frame being provided with inner and outer arms, a hollow member adapted to fit over the outer arms of said awning frame and bridge the gap between said arms when said awning frame is adjusted, another hollow member fitted over 45 the inner arms of said awning frame, said second-named hollow member being provided with perforations to receive screws adapted to enter said last-named arms of said awning frame when said awning frame is in adjusted 50 position, an arm secured to each of the two inner corners of said awning frame and each of said arms being provided with an opening therein to receive a movable securing member, and a threaded bolt associated with said arm and contacting with said movable member whereby said movable member is caused to lock said awning frame in an automobile window casing, substantially as described.

In testimony that I claim the foregoing I 55 hereunto affix my signature.

CHARLES E. HENDRIX.
